UNITED STATES PATENT OFFICE.

ARTHUR G. ROGERS, OF MERIDEN, CONNECTICUT, ASSIGNOR TO C. ROGERS & BROS., OF MERIDEN, CONNECTICUT, A CORPORATION.

DESIGN FOR A HANDLE FOR SPOONS, FORKS, OR SIMILAR ARTICLES.

SPECIFICATION forming part of Design No. 35,502, dated December 31, 1901.

Application filed November 22, 1901. Serial No. 83,348. Term of patent 7 years.

all whom it may concern:

Be it known that I, ARTHUR G. ROGERS, of Meriden, in the county of New Haven and State of Connecticut, have invented and produced a new and useful Design for a Handle for a Spoon, Fork, or Similar Article; and I do hereby declare the following, when taken in connection with the accompanying drawing and the letters of reference marked thereon, to be a full, clear, and exact description of the same, and which said drawing constitutes part of this specification and represents a face or plan view of a handle for a spoon, fork, or similar article embodying my design.

This invention relates to a design for a handle for a spoon, fork, or similar article; and the invention consists in the configuration and ornamentation of the handle, as hereinabove described, and shown in the accompanying illustration.

As herein shown, at the outer end of the

handle is a central scroll A, and on opposite sides are scrolls B, forming a trefoiled tip. The sides of the handle are gradually tapered ²⁵ inward and are ornamented by reversibly-turned scrolls C, D, and E, which are connected by a scroll F, inclosing a panel G. On each side of the handle is a long scroll H, meeting a conventionalized scroll I at the inner end of the handle. ³⁰

Having fully described my invention, what I claim as new, and desire to secure by Letters Patent, is—

The design for a handle for a spoon, fork, ³⁵ or similar article, as herein shown and described.

In testimony whereof I have signed this specification in the presence of two subscribing witnesses.

ARTHUR G. ROGERS.
